UNITED STATES PATENT OFFICE.

CHARLES WHITE AND ARTHUR R. MIDDLETON, OF BALTIMORE, MARYLAND.

EXPLOSIVE-ENGINE.

No. 842,737.

Specification of Letters Patent.

Patented Jan. 29, 1907.

Application filed June 22, 1904. Renewed November 23, 1906. Serial No. 344,786.

To all whom it may concern:

Be it known that we, CHARLES WHITE and ARTHUR R. MIDDLETON, citizens of the United States, residing at Baltimore, Maryland, have 5 invented certain new and useful Improvements in Explosive-Engines, of which the following is a specification.

Our invention concerns more particularly means for controlling the feed of fuel to the engine.

Explosive-engines are governed by cutting off the supply of fuel to the combustion-chamber for the required period, the governor mechanism being adapted and arranged to 15 cut off the supply when required in order to reduce the speed and to maintain a regular and uniform supply while the engine is moving under normal conditions of load and speed.

With explosive-engines using gasoline for fuel serious difficulty is experienced by reason of the necessary irregularity of the feed of the fuel produced by the governor in meeting the different conditions, such difficulty being 25 due to the volatile nature of the fuel and to the altered conditions in the combustion-chamber arising from the cutting off of this combustible fluid for one or more strokes, allowing the conditions of temperature and moisture within the explosion-chamber to become 30 abnormal.

In our engine, while we employ the method of governing consisting of cutting off the supply of fuel for the required period, we vary the 35 charges as to the proportion of gasoline so as to make up for the changed conditions within the combustion-chamber. We do this by holding the induction-valve closed during the time that the fuel-supply is ordinarily cut off 40 and by feeding in rear of said closed valve a small initial charge of fuel which upon the next opening of the valve passes into the combustion-chamber with the next main charge allowed by the governor, so that this 45 main charge, which is the first one supplied after cutting off, is in excess in volume to that which is supplied while the engine is running normally and charges are regularly supplied thereto. This excess or initial charge 50 compensates for the changed conditions in the explosion-chamber arising from the want of charges fed thereto with regularity.

The invention consists in the features and combination and arrangement of parts hereinafter described, and particularly pointed out in the claims.

In the accompanying drawings, Figure 1 is a side elevation of the gasoline-engine with our improvements attached. Fig. 2 is a detailed view of the pump for the gasoline. Fig. 3 is 60 a detail view of governor mechanism; and Fig. 4 is a detail plan view, partly in section, of the head of the cylinder with the valve mechanism carried thereby.

In the drawings the cylinder 1 is of substantially ordinary construction, and to this cylinder an air-pipe 2 extends, connecting with a box 3, which is connected through the port 4 with the combustion-chamber 5 of the engine, the said port 4 being controlled by an induction-valve 6. Gasoline is supplied to the engine from a suitable reservoir through a pipe 7, leading to a pump 8, said pump connecting with the box 3, before mentioned, and thus supplying the liquid fuel to the port 4 75 and inlet-valve 6.

The pump comprises a piston 9, which has a rod 10 extending outside of the piston-casing and operated by an arm 11 on a governor-rod 12, extending alongside of the engine 80 from the governor mechanism, as will be hereinafter described. The arm 11 has a set-screw 13 adjustably held therein to bear on a nut 14 on the piston-rod 10. A spring 15 is arranged on the piston-rod to hold the 85 piston in retracted position. Check-valves 16 and 17 are arranged, respectively, in the pipe leading to the pump and in the nozzle 18, extending from the pump into the box 3, said check-valves coöperating with the pump 90 in supplying the liquid fuel to the engine. The rod 12 is arranged in a manner and performs functions similar to those described in our Letters Patent of the United States No. 545,995, September 5, 1895, in that the said 95 rod extends from the governor mechanism alongside of the cylinder and through a portion of the cylinder-head at 19, its rear end bearing against a lever 20, pivoted to the standard 21 on the rear end of the cylinder, 100 the said lever at its opposite end bearing upon the stem 22 of the supplemental exhaust-valve 23, the said exhaust-valve controlling the exhaust-port 24 and being under tension of a spring 25, tending constantly 105 to seat the said valve.

The governor mechanism comprises a slide 26, movable in a casing 27, supported on any suitable part of the frame, the said slide carrying a roller 28, operated by a cam 29 on a shaft 30, which shaft is driven through gearing 31 32 from the crank-shaft 33 of the en-

gine. The slide 26 carries a stop 34, said stop being held thereto adjustably by a screw 35, and a set-screw 36 with a jam-nut 37 also forming part of the means for adjusting the stop. This stop is adapted to strike a governor-detent 38, pivoted to the casing 27 or to any other suitable stationary part at 39, the said detent being connected by a link 40 and a lever 41, pivoted at 42 to a sleeve 43 of the governor mechanism 44, which sleeve is adapted to be moved vertically, and thus raise and lower the detent into and out of the path of the stop 34 on the slide 26. The arrangement is such that when the speed of the engine increases the cut-off takes place by the governor operating to depress the end of the detent 38 into line with the stop 34, so that the said stop will arrest the movement of the slide 26 and rod 12 to the right in Figs. 1, 3, and 4, and thus the cam 29 in its revolution will not operate the rod 12, and consequently the pump will not be actuated and the supply of fuel will be cut off. The rod 12, it will be understood, is pressed constantly toward the right by a spring 45, Fig. 4, bearing against a collar 46 thereon. As soon as the speed of the engine lowers to normal the governor-detent 38 will be raised, and the spring 45 will then move the rod 12, so that the roller 28 on the slide will again be brought into the range of action of the cam 29, and said cam will, together with the spring 45, reciprocate the rod 12, and consequently the pump will be operated and the fuel will be supplied to the engine.

As before stated, in the use of gasoline as a fuel when the cut-off of the fuel takes place and the engine runs without fuel being supplied thereto the conditions in the combustion-chamber are changed, the supplemental exhaust-valve being at this time open, as shown in Fig. 4, and the combustion-chamber being cleared of the exhaust products. By reason of the changed conditions within the combustion-chamber we have found it necessary to compensate therefor by supplying an excess of fuel in the first charge, which is fed to the engine upon resuming the fuel-feeding actions. In order to accomplish this, we provide means for holding the inlet-valve closed during the cut-off period, and we supply to the space or port immediately in rear of this valve a small initial charge of fuel, which is regulated in quantity to correspond to the period of cut-off—that is to say, if the cut-off period is short the initial or excess charge is small, whereas if the cut-off period is long the initial or excess charge is larger. For holding the inlet-valve closed when the supplemental exhaust-valve is open during the cut-off period we provide an arm 47, connected with the rod 12 and having its free end bearing upon a collar at 48 on the stem 49 of the said inlet-valve, which

keep the inlet-valve closed. The arm 47 is of flexible material, and it is so arranged that when the inlet-valve is closed, as shown in Fig. 4, the said arm is under tension and the rod 12 may have a slight reciprocatory movement without affecting the holding action of the said flexible arm upon the inlet-valve 6—that is to say, the arm 47 will maintain the inlet-valve closed, while at the same time the rod 12 may have slight reciprocatory movement, and this reciprocation of the rod 12 will operate the gasoline-pump to a small degree, and fuel will therefore be fed to the space or port in rear of the closed inlet-valve. In order to secure this feeding action, it is simply necessary to adjust the stop 34 in relation to the governor-detent 38 so that there will be a small clearance between these two when the roller 28 is on the high point 29^x of the cam 29. It will be observed from this that as the cam rotates the slide 26 will be reciprocated to the extent of this clearance during the cut-off period, or, in other words, so long as the governor-detent remains in its lowermost position, and thus during this time the fuel will be fed back of the closed inlet-valve, and immediately upon the resumption of the normal feed of the fuel this excess or initial small charge will add itself to the main charge which is first let in after the cut-off period, so that the said excess charge will be sufficient to compensate for the drying out and other changed conditions which have taken place in the combustion-chamber during the cut-off period.

It will be seen from the above that by utilizing an arm 47 of a flexible character a simple and effective construction is provided, and the same rod 12 which operates the pump and the supplemental exhaust is utilized for operating the flexible arm and keeping the inlet-valve closed. While we prefer this arrangement, we do not wish to be limited in this respect. The arm 47, besides serving to hold the inlet-valve closed, also by reason of its flexibility serves to cushion the action of the inlet-valve and relieves the spring 50 of shock. It also serves to cushion the closing movement of the valve.

We claim—

1. In combination, in an explosive-engine, a cylinder valve mechanism, and means including a governor for feeding an excess charge of fuel to the combustion-chamber after the cut-off period has terminated, substantially as described.

2. In combination, in an explosive-engine, a cylinder, valve mechanism, including an inlet-valve held closed during the cut-off period, means for supplying fuel and governor means for feeding a small charge back of the closed inlet-valve during the cut-off period, substantially as described.

3. In combination, in an explosive-engine,

- an exhaust-valve at the rear end of the combustion-chamber, an inlet-valve, means for holding the exhaust-valve open and the inlet-valve closed, and governor means for feeding back of the closed inlet-valve a small charge of fuel prior to the feeding of the main charge, substantially as described. 5
4. In combination, in an explosive-engine, an inlet-valve, a governor-rod, a fuel-supplying device operated by the said rod and a yielding connection between the said rod and the said inlet-valve arranged to keep the said valve closed while the rod reciprocates to feed the fuel, substantially as described. 10
5. In combination, in an explosive-engine, an inlet-valve for the fuel, a fuel-supplying device, a rod for operating the said device, and a flexible arm connecting the said rod with the inlet-valve to hold the said valve closed while the rod operates the fuel-supplying device. 15
6. In combination, in an explosive-engine, an inlet for the fuel, an exhaust-valve, an intermediately-pivoted lever for operating the exhaust-valve by bearing at one end thereon, a governor-rod bearing at the other end of the lever to operate the same, and an arm extending from the said rod to hold the inlet-valve closed while the exhaust-valve is open, substantially as described. 20
7. In combination, in an explosive-engine, an inlet-valve for the fuel, an exhaust-valve, a lever for operating the exhaust-valve, a governor-rod for operating the lever, fuel- 25
- supplying means operated from the said rod and yielding means connecting the said rod with the inlet-valve to hold the same closed while the rod operates the fuel-supplying means, substantially as described. 35
8. In combination, in an explosive-engine, an inlet-valve for the fuel, a fuel-supply device, means for operating the said device comprising a slide having a stop, a cam for operating the slide, and a detent for engaging the stop, having clearance therewith to allow 40 movement of the slide when the governor cuts off, substantially as described. 45
9. In combination, in an explosive-engine, an inlet-valve for the fuel, an exhaust-valve, a fuel-supplying device, a rod for operating the same, a lever operated by the said rod and controlling the exhaust-valve, a flexible arm connecting the said rod with the inlet-valve, a cam for operating the rod, a stop associated with the rod, and a governor-device 50 for controlling the stop, said detent having clearance between itself and the stop to allow the rod to be operated by the cam partially when the cut-off takes place, substantially as described. 55
- In testimony whereof we affix our signatures in presence of two witnesses. 60
